UNITED STATES PATENT OFFICE

WALTER F. MILLER, OF FREEHOLD, NEW JERSEY, ASSIGNOR TO A. & M. KARAGHEUSIAN, INC., OF NEW YORK, N. Y., A CORPORATION OF DELAWARE

PILE FABRIC

Application filed October 18, 1929. Serial No. 400,572.

This invention relates to the art of weaving pile fabrics.

An object of the invention is the provision of an improved form of rug weave adapted to produce, from a relatively small number of primary color yarns, a fabric having, in appearance, a pattern containing many more colors.

Another object is the provision of a method of weaving whereby a loom of a given number of frames may be used to produce a fabric pattern appearing to include many more colors than said given number.

A further object is to provide a method of weaving, on a Jacquard loom, a two shot pile fabric having the same pattern on the front side and back side.

In accordance with my invention I produce, from several primary colors a larger number of color effects in the pattern of a finished pile fabric, by arranging in the openings formed between intersecting pairs of binder and filler threads, pile threads of different colors in equal numbers. In most cases one thread of one color and a second thread of a different color will be used in each opening, but more than one thread of each color may be furnished if desirable. This arrangement of the pile produces an intimate mixture of yarns of two or more primary colors, which creates the optical illusion of a third and different, or secondary color, by a blending of said primary colors. It is, therefore, possible, for example, to produce on a three frame loom a fabric having three primary colors and three secondary colors, or blends.

I may obtain this effect on a Jacquard loom arranged to produce Brussels or Wilton type fabric, and at the same time produce the same pattern front and back on the fabric, by making a two shot weave wherein the warp yarn used to produce a tuft in the pattern is carried below a first shot of the ground weft, over the second and third and under the fourth shot. The warp yarn forming the second and differently colored tuft longitudinally of the fabric is carried below the third shot of ground weft, above the fourth and fifth and under the sixth shot.

The above mentioned and other objects and advantages and the manner of attaining them will be made clear in the following description and accompanying drawings.

In the drawing Fig. 1 is a diagram illustrating my improved method of weaving pile fabrics. The diagram shows the operation in connection with a single series of pile warp threads of a three frame fabric, it being understood that the other series of pile warp threads may be manipulated in a similar manner, in the production of a complete fabric.

Fig. 2 is a face view of a finished fabric showing the color blending effect.

Referring more particularly to the drawings reference numerals 1 and 2 indicate the ground chain threads which pass over and under alternate shots of the weft 3, 4, 5, 6, 7, 8 in the usual manner.

9 indicates a pile color thread, for example, blue, which passes below weft shot 3, producing the pattern on the back of the fabric, then over weft shot 4 and pile wire 9^a and finally over weft shot 5 and under weft shot 6 to an inactive position between successive shots, where it lies until again needed for the pattern. The next color thread appearing in the pattern, indicated by 10, which may be red, passes under weft shot 5, then over weft shot 6 and wire 11 and finally over shot 7 and under shot 8 to an inactive position.

Upon withdrawal of the pile wires 9^a, 11, the pile loop may or may not be cut, depending on the type of wire used. If the loop is cut two thread ends of different colors appear side by side in opening 12, formed between pairs of weft threads, for example, 15, 16 and the cooperating binder and ground chain threads. If the two colors blue and red are alternated lengthwise and crosswise of the fabric a secondary purple color effect is produced in the pattern, as indicated in Fig. 2, at 13. In like manner other color combinations may be produced, for example, green and yellow may be combined to produce a lighter green, or black may be mixed with green to produce a deeper green. The illusion is so perfect that at a distance of several feet the mixed colors blend together com-

pletely and appear to be an entirely different color or shade altogether.

In accordance with this invention a five frame fabric, wherein a single thread is used to produce a pile loop, may be made with a pattern appearing to have fifteen different colors or shades. If more than one color of yarn be used for a single pile loop additional colors and shades might be obtained. When the pile is cut, as in a Wilton carpet, the ends of the cut yarn spread out and intermingle so that the color illusion is even better than in the uncut or Brussel type of fabric. But it will be understood that the invention may be used successfully with a fabric having uncut pile as well as with one having cut pile.

If it is desired to produce a pattern solely of primary colors, which will appear both front and back on the fabric this may be done, still in two shot manner, by causing the color yarn to pass over and under successive weft shots as indicated by 14, at the right hand end of Fig. 1.

It will be obvious to those skilled in the art that the invention is capable of various modifications and adaptions and that the present disclosure is intended merely to illustrate its nature without limiting its scope, which is defined in the following claims.

What I claim is:

1. A two shot multi-color pile fabric the pattern of which is formed of a plurality of yarn threads of different individual colors, comprising a plurality of weft shots interwoven with ground chains, wherein a pattern forming yarn passes under a first weft shot, over a second weft shot and above the ground chain to form a pile loop, and finally over a third shot and under a fourth shot.

2. A pile fabric in accordance with claim 1 wherein said pattern forming yarn is of one color and a second pattern forming yarn is interwoven, said second yarn being of a different color and passing under the third weft shot, over the fourth and above the ground chain to form a pile loop, over the fifth and under the sixth shot.

3. A single pile two shot multi-color fabric having the same pattern on the back side and front side wherein two pattern forming threads, each of a different color are positioned side by side and interwoven with weft shots and a binder chain, one of said threads passing under a first weft shot, over the second and above the ground chain to form a pile loop, over a third shot, and under the fourth and fifth shots, and the other of said threads passing under said third shot, over said fourth and above the ground chain to form a pile loop, over a fifth shot, and under a sixth shot.

In testimony whereof, I have signed my name to this specification this 27th day of September, 1929.
